FLUSH SYSTEM ARRANGEMENT

BACKGROUND OF THE INVENTION

This invention relates to a flush system arrangement and, more particularly, to a flush arrangement for a reservoir, as, for example, in a humidifier, which has no moving parts and is adapted to wash all residue accumulated on the bottom of the reservoir down a drain opening.

When water evaporates, mineral salts remain. The amount of residue is dependent upon the quality of the water, which can vary considerably between different locations. It is desirable that this residue be removed from the reservoir.

One method of cleaning the residue from the bottom of a reservoir has been to remove the reservoir from the humidifier and manually clean same. Some reservoirs have been provided with a drain opening in the bottom and a stream of water was flushed through from a hose from above to clean out residue from the bottom of the reservoir. However, in some arrangements, access to the top of the reservoir was difficult, making this method not feasible.

An object of the present invention is to provide a flush system arrangement for a reservoir, as, for example, in a humidifier, which requires no moving parts and is easy to fabricate and maintain.

Another object of the present invention is to provide a flush system arrangement for a reservoir comprising a distribution channel having slotlike openings therein constructed and arranged to create successive whirlpools adjacent the bottom of the reservoir for flushing all residue on the bottom toward a drain opening. Other objects and advantages of the present invention will be made more apparent hereinafter.

BRIEF DESCRIPTION OF THE DRAWING

The specific details of a presently preferred form of the present invention and their mode of operation will be made most manifest and particularly pointed out in clear, concise and exact terms in conjunction with the accompanying drawing, wherein:

FIG. 1 is a perspective view of a humidifier embodying the present invention with parts being broken away for clarity;

FIG. 2 is a side view of the humidifier of FIG. 1, with a side cover removed to more clearly illustrate the reservoir pan assembly therein;

FIG. 3 is a plan view of the reservoir pan assembly;

FIG. 4 is a cross-sectional view of the reservoir pan assembly taken generally along the line 4-4 of FIG. 3;

FIG. 5 is a cross-sectional view of the reservoir pan taken generally along line 5-5 of FIG. 4; and

FIG. 6 is a cross-sectional view of the reservoir pan taken generally along line 6-6 of FIG. 4.

DESCRIPTION OF THE PREFERRED FORM OF THE INVENTION

Referring now to FIGS. 1 and 2, there is illustrated a humidifier 10 embodying the flush cycle of the present invention. Basically, the humidifier 10 comprises a base or frame 11 which is adapted to be mounted to a duct or air plenum 14. Housing 12 encloses the base 11 and components secured thereon. The humidifier 10 may be mounted either in the return or supply air plenum to a furnace 15. Provided within the housing 12 on base 11 are components for controlling the fill cycle, the humidification cycle and the flush cycle.

The fill cycle is independent of humidification operation and is controlled by the following components: a circuit board 16, water level probes 18, 19 and 20, fill valve 21 and a control transformer 23. The control transformer 23 is adapted to convert line voltage, normally 110 volts, to control voltage, normally 24 volts. As will be set forth in more detail hereinafter, the fill valve 21 is normally operative in order to maintain a constant water level within the reservoir means 25.

Water evaporation is accomplished within the humidifier 10 by the following components: heating element 26, control relay 28, the control transformer 23 and a humidistat, not

shown, which is adapted to be mounted in the room to be conditioned or the air plenum.

The flush system operates to remove residuals from the reservoir. Included in the flush system are flush valve 30, the fill valve 21, the control transformer 23, clock timer 32 and drain means 34 operatively connected to the reservoir means 25. The timer 32 is responsive to the fill valve and will record accumulated fill cycle time and initiate a flush cycle at the end of 3 minutes of fill cycle time.

In operation, whenever the humidistat (not shown) senses a need for more humidity, it energizes the control relay 28, which, in turn, energizes the heating element 26. At the same time, the system blower (not shown) in the furnace 15 will be started, if it has not already been placed in operation. When the humidistat is satisfied, the control relay 28 is deenergized, shutting off the heating element 26. The system blower will also be deenergized at this time provided that the blower operation is not required by other controls.

During normal operation, the power and the water supply to the humidifier is left operative and it will be understood that during the summertime or other periods where humidification is not required, the humidistat is set to an off-position, whereby the heating element 26 will be rendered inoperative.

Considering briefly the operation of the flush cycle, the clock timer 32 is operative to open the flush valve 30 and fill valve 21. Water will flow into the distribution channel 36 within the reservoir means 25 and be discharged therefrom in a specific manner, so as to flush residuals from the elongated flat bottom of the reservoir means 25 into the drain means 34. The flushing continues for approximately 3½ minutes. Then, the flush valve 30 closes and the fill cycle controls take over to shut off the fill valve 21 after the reservoir has again been filled to a predetermined level.

Also provided within the housing 10 is a two-stage safety overflow protection arrangement, which includes an overflow safety probe 38. Formed in the bottom of drain compartment 40 in the reservoir means 25 is an overflow drain opening 62 which communicates directly with the drain body 41 that in turn is connected to a drain conduit 44. The flush valve 30 extends into the drain body 41 for controlling the flow from a drain opening 60 in the bottom of the main compartment of the reservoir pan and drain body may be formed from a suitable noncorrosive plastic material as, for example, Polysulfone. Preferably, the reservoir means is made from a transparent material, so that the interior thereof can readily be viewed.

In the event of failure of either the flush valve 30, or the fill valve 21, water will be communicated from the main compartment defined in the reservoir means 25, through the independent overflow drain compartment 40 within the reservoir means 25 and the drain body 41 to the carry-off drain 44. The overflow safety probe 38, which is in circuit with the components on circuit board 16, will shut off the fill valve 21 in the event the drain line becomes plugged.

Also provided in the humidifier 10 is a safety limit control 46. The control 46 is a hermetically sealed thermal fuse, which is in circuit with the heating element 26 and will function to terminate operation of the heating element 26 if the temperature within the reservoir means 25 exceeds a predetermined value, as, for example, 220° F. The bracket 47 helps support the drain body 41 in the housing 12.

Turning now to FIGS. 3, 4, 5 and 6, there is better illustrated the construction of the reservoir means 25, and, more particularly, the distribution arrangement within the reservoir means 25 for effecting a flushing of all residue from the planar bottom of the reservoir means 25 to a drain body 41 and then to drain conduit 44. The reservoir means 25 comprises a generally boxlike member having a bottom 48, substantially upright sides 49 and 50 and front and rear walls 51 and 52. The overflow compartment 40 at one side of the reservoir means 25 is defined between an intermediate transverse wall 54, front wall 51, rear wall 52 and sidewall 50. Water is sup-

plied to the reservoir means 25 through water inlet 56a in inlet means 56. The water inlet 56a is adapted to communicate with the fill valve 21. The inlet means 56 comprises the water inlet opening 56a communicating with the distribution channel 36 and an inlet opening 56 for receiving the heater element. The water is adapted to be discharged from the reservoir means 25 through a drain opening 60, which communicates with the drain body 41. A separate drain opening 62 is provided in the bottom of the overflow drain compartment 40 for communicating the drain compartment 40 with the drain body 41 and the drain conduit 44.

Wall means 68 at the rear of the reservoir means 25 cooperate with wall 52 to define an overflow compartment 69 for receiving water from the main reservoir compartment 48 and conveying same into the overflow compartment 40.

Defined at the front of the reservoir means 25 is a forwardly extending U-shaped wall member 70, which cooperates with wall 51 to define a small chamber 72 which communicates with chamber 48 and receives the water level probes 18, 19 and 20 therein.

By reference to FIGS. 3 and 4, it is seen that flanges 76 and 78 extend outwardly from the sides of the reservoir means 25. Formed in the flanges are key hole type slots 77 and 79, respectively, for facilitating connection of the reservoir means 25 to the base 11 of the humidifier 10. It will be understood that suitable headed pins, screws or the like members are secured to the housing 12 and extend outwardly therefrom. The large portions of the key hole slots 77 and 79 are adapted to fit over the headed pins and then upon movement of the reservoir means 25 downwardly, the smaller portion of the key hole slots 77 and 79 engage with the shanks of the headed pins, whereby the reservoir means will be retained in position within the housing 12.

A feature of the present invention is the arrangement for flushing all residue from the flat elongated bottom of the reservoir means. The distribution channel 36, which is positioned in the reservoir means had slotlike openings therein, which are constructed and arranged to create successive whirlpools within the reservoir, which whirlpools cooperate with one another in the manner of an auger to move residue from one end of the reservoir adjacent the inlet means 56 toward and through the drain opening 60 adjacent the other end of the reservoir. The distribution channel 36 is defined by a generally inverted U-shaped member adapted to have one side 80 thereof abut the front wall 51 of the reservoir means and having the other side 82 adapted to abut a flange 74 extending upwardly from the bottom 48 of the reservoir to help retain the distribution channel 36 in place.

Provided in the wall 82 of the distribution channel 36 are a plurality of slotlike openings 84. The openings 84 extend upwardly from the bottom of the reservoir and are disposed at an acute angle with respect to the longitudinal axis of the distribution channel 36 to create a plurality of successive whirlpools along the length of the distribution channel. The distribution channel includes an end wall 85 having an elongated slotlike opening 86 therein, which is similar to the slotlike openings 84. As best seen in FIG. 4, the top wall of the distribution channel is inclined downwardly and converges with the bottom toward end wall 85. The arrows in FIG. 3 indicate generally the water discharge pattern created by the water discharging from each of the openings 84 and 86.

Provided in the wall 51 of the reservoir are a plurality of openings 89 and 90 for permitting water to pass from the main chamber within the reservoir means 25 into the chamber 72 defined on the forward portion of the reservoir means for receiving the probes 18, 19 and 20.

In the event that there should be a stoppage of the drain opening 60, or malfunction of flush valve 30, water will overflow from the main compartment in reservoir means 25 through the recessed portion 92 in the rear wall 52 into the overflow chamber 69 defined to the rear of the reservoir

means 25. The water will then flow from the overflow chamber 69 into the drain compartment 40 through an access opening provided by a recessed area 94 defined in the rear wall 52. From the drain compartment 40, the water will be discharged through the drain hole 62 into the drain body 41, and then into the conduit 44.

The elongated slots 84 and 86 within the distribution channel 36 are disposed in a manner to effect most desirable movement of residues from the bottom 48 of the reservoir pan 25 to the drain. The openings 84 extend upwardly from the bottom of the reservoir and are disposed at generally a 45° angle with respect to the longitudinal axis of the distribution channel 36. Further, the openings 84 are spaced equally along the length of the distribution channel and in a presently preferred form of the invention, there are five such openings 84. A similar opening 86 is provided in the sidewall 85 of the distribution channel for creating a like whirlpool in the area adjacent the drain 60. Opening 86 extends upwardly from the bottom of the reservoir means. The axis of the opening 86 diverges about 3° from the longitudinal axis of the distribution channel. As an example of the relative size of the openings in one presently preferred form of the invention, the distribution channel is about 6 1/4 inch long and the openings 84 are spaced 1 9/16 inch wide by 7/32 inch high. The opening 86 is approximately 1/8 inch wide by 3/32 inch high.

While I have shown a presently preferred form of the invention, it is obvious that it is intended in the appended claims to cover all such changes and modifications as may be within the true spirit and scope of the invention.

I claim:

1. A reservoir flush arrangement comprising an elongated reservoir pan having an inlet opening and outlet opening, said outlet opening being in the bottom thereof, distribution means in said pan adjacent one side of said bottom communicating with said inlet opening for receiving fluid and discharging same onto said bottom to flush all residue on said bottom into said outlet opening, said distribution means including wall means having a plurality of openings therein for discharging jets of fluid in a predetermined fashion from said distribution means to create successive whirlpools along the bottom to move residue toward the outlet opening, said plurality of openings comprising a plurality of slots spaced apart along the major axis of the reservoir pan in said wall means.

2. A reservoir flush arrangement as in claim 1 wherein said slots extend upwardly from adjacent the bottom of said reservoir pan and said slots are greater in height than in width.

3. A reservoir flush arrangement as in claim 1, wherein the outlet opening is at one end of the reservoir pan and the slots are angled with respect to the major axis of the reservoir pan for discharging jets of fluid so as to create successive swirls of fluid to flush all residue toward said one end of the reservoir pan and into said outlet opening.

4. A reservoir flush arrangement as in claim 1, wherein said bottom is flat and elongated.

5. A reservoir flush arrangement as in claim 4, including means for controlling flow of fluid to said inlet opening to periodically introduce fluid into said distribution means for flushing the bottom of said reservoir pan. A reservoir flush arrangement as in claim 5 wherein said reservoir pan includes a main compartment and a separate drain compartment having a drain outlet therein, and an overflow compartment for receiving fluid from said main compartment and conveying same to said separate drain compartment.

6. A reservoir flush arrangement as in claim 1 wherein the internal cross section of the distribution means is reduced uniformly from the inlet end toward the opposite end.

7. A reservoir flush arrangement as in claim 6 wherein a drain body is disposed beneath the reservoir pan for receiving fluid discharged both from the outlet opening and the drain outlet.
